UNITED STATES PATENT OFFICE.

HIRAM S. DOTTs, OF MARIANNA, PENNSYLVANIA.

CIGAR-TIP-PROTECTING LABEL.

1,163,225.

Specification of Letters Patent.

Patented Dec. 7, 1915.

Application filed June 1, 1915. Serial No. 31,461.

To all whom it may concern:

Be it known that I, HIRAM S. DOTTs, a citizen of the United States, residing at Marianna, in the county of Washington and State of Pennsylvania, have invented certain new and useful Improvements in Cigar-Tip-Protecting Labels, of which the following is a specification, reference being had therein to the accompanying drawing.

10 This invention relates to certain new and useful improvements in cigar tip-protecting labels, the object being to provide a combination tip protector and label so constructed that the label will be held in position on the cigar by the tip protector.

Another object of my invention is to provide a cigar tip-protecting label which comprises a protector having a label connected thereto provided with a scratching surface 20 on its under side, said protector being held in position upon the cigar by a match which perforates the tip thereof in order to form a draft flue.

Another object of my invention is to provide a cigar tip protector in the form of a conical cap-shaped member adapted to fit over the tip of the cigar having a label connected thereto in such a manner that when the cap is removed, by withdrawing the 30 match used for securing the same in position upon the cigar, the label will be removable, thereby overcoming the disadvantages now existing in band labels.

Other and further objects and advantages 35 of the invention will be hereinafter set forth and the novel features thereof defined by the appended claims.

In the drawings—Figure 1, is a perspective of my improved construction of cigar 40 tip-protecting label, showing the application of the same to a cigar; Fig. 2, is a longitudinal section through the protector and label showing the same in position on a cigar; Fig. 3, is a perspective of a cigar tip-protect- 45 ing label and match detached; Fig. 4, is a similar view showing a slightly modified form of tip-protecting label; Fig. 5, is a plan view of the blank from which the form of tip-protecting label as shown in Fig. 4, is 50 made; Fig. 6, is a longitudinal section through a slightly modified form of tip-protecting label showing the tip and label made separately and attached to the cigar by a match; and Fig. 7, is a detail inverted 55 plan view of a label showing the scratching

surface for igniting the match used for holding the tip-protecting label in position upon the cigar.

Like numerals of reference refer to like parts in the several figures of the drawings. 60

In the form of tip-protecting label as shown in Figs. 1, 2 and 3, I provide a conical cap-shaped member 1 adapted to embrace the tip of the cigar having an opening in the apex thereof through which a match 2 is 65 adapted to be inserted, which penetrates the tip of the cigar so as to perforate the same so as to provide a draft flue in the tip of the cigar without cutting the same; said cap-shaped member having a label 3 secured 70 thereto provided with a scratching surface 4 on its under side, by means of which, the head of the match can be ignited after the same has been withdrawn from a cigar in order to light the same. In this form of 75 cigar tip protector, the label is in the form of a strip having a label-bearing end, and a portion which is secured upon the outer surface of the conical cap-shaped member by any suitable adhesive material. 80

In the form shown in Figs. 4 and 5, the cigar tip-protecting label is formed of a blank as shown in Fig. 5, comprising a circular portion 5 bent into substantially conical shape and fluted so as to allow the same 85 to expand and contract to accommodate cigars of various sizes. Extending from the circular portion is a label 6. In this form the conical cap-shaped member and label are formed integral, the cap member being secured in position by a match 7 in a similar manner to that described in Figs. 1, 2 and 3. 90

In the form shown in Fig. 6, I provide a conical cap-shaped member 8 and a label 9 formed separate, the strap of the label being 95 passed over the tip of the cigar before the cap is inserted so that when the match 10 is passed through the opening thereof, the label will be secured in position upon the cigar. 100

From the foregoing description, it will be seen that I have provided a cigar-tip-protecting label so constructed that a label is provided for a cigar and a protector for the tip thereof, the same being secured in position upon the cigar in such a manner that a draft flue is formed for the cigar, without cutting the same. 105

It will also be seen that by the construction as above described, when the match is with- 110

drawn so as to remove the protecting cap, the label is also removed, thereby overcom-
ing the difficulties now existing in band
labels, as the label is removed without danger
5 of injuring the wrapper of the cigar so as
to prevent the drawing of the same, when be-
ing smoked.

I claim:

1. A cigar tip-protecting label, comprising
10 a conical cap-shaped tip-protecting
member, having a label extending therefrom
provided with a scratching surface.

15 2. A cigar label, comprising a tip-protect-
ing member adapted to inclose the tip of the
cigar and having a label connected thereto
adapted to embrace the cigar upon which the
member is arranged, said protecting member
having an opening to receive a match for

attaching the same to a cigar, and a scratch-
ing surface formed on said label.

20

3. A cigar tip-protecting label, comprising
a conical fluted cap-shaped member, hav-
ing a label extending therefrom provided
with a scratching surface.

4. A cigar tip-protecting label, comprising
25 a conical fluted cap-shaped member hav-
ing an opening to receive a match for attach-
ing the same to a cigar and provided with a
label having a scratching surface.

In testimony whereof I affix my signature 30
in presence of two witnesses.

HIRAM S. DOTT.
